CLAIM

The ornamental design for a vehicle tire, substantially as shown and described.

DESCRIPTION

FIG. 1 is a perspective view of a vehicle tire showing my new design, it being understood that the tread pattern is repeated throughout the circumference of the tire and the opposite side is the same as that shown; FIG. 2 is a side elevational view thereof; FIG. 3 is a front elevational view thereof; and FIG. 4 is an enlarged fragmentary plan view thereof.
